Primary Examiner — Mitchell I. Siegel

(57) **CLAIM**

The ornamental design for a golf ball alignment aid, as shown and described.

DESCRIPTION

FIG. 1 is a top view of a golf ball incorporating a golf ball alignment aid;

FIG. 2 is a bottom view of the golf ball of FIG. 1;

FIG. 3 is a front view of the golf ball of FIG. 1, the undisclosed rear being identical; and,

FIG. 4 is a side view of the golf ball of FIG. 1.

The broken lines shown on the drawings form no part of the claimed design.
